UNITED STATES PATENT OFFICE.

BENJAMIN W. TUCKER, OF NEWARK, NEW JERSEY.

DESIGN FOR A SIDE FRAME FOR CAR-TRUCKS.

SPECIFICATION forming part of Design No. 26,904, dated April 18, 1897.

Application filed February 27, 1897. Serial No. 625,426. Term of patent 14 years.

To all whom it may concern:

Be it known that I, BENJAMIN W. TUCKER, a citizen of the United States, residing at Newark, in the county of Essex and State of New Jersey, have invented and produced a new and original Design for the Side Frame of Car-Trucks; and I do declare the following to be a full, clear, and exact description of the same, reference being had to the accompanying drawings, forming a part thereof.

In the drawings, Figure 1 is a side elevation of the side frame of a car-truck embodying my design. Fig. 2 is a like view of same, looking at the inner side of said side frame; and Fig. 3 is a vertical section of same on the dotted line 3 3 of Fig. 1.

The leading features of my design consist in the form and configuration of the side frame for a car-truck, substantially as shown and described.

In the drawings, A designates the side frame, which, as shown in Fig. 1, has a plain outer face and, as illustrated in Fig. 2, has along the upper and lower edge portions of its inner face the lateral flanges B C.

The side frame A has the downwardly-extending members or portions D D, along which the flange C continues on a curved line, as shown in Fig. 2, and said frame also

has the upper horizontal members E E and outer vertical members F F, along which the upper flange B extends. The members D E F combine with the vertical end edges a a of the main frame A to outline the rectangular pedestal-spaces G. The thickness and width of the flanges B C continue uniform throughout the entire length of said flanges. At the end edges of the web of the main frame A are the right-angle pieces H, whose outer vertical transverse flange I combines with the thickness of the said web to form a pedestal-surface harmonizing and coextensive in width with the width of the vertical flanged members F.

The parts of the side frame harmonize with one another to produce an outline and general configuration of attractive and desirable characteristics.

What I claim is—

The design for the side frame of a car-truck, substantially as shown and described.

In testimony whereof I affix my signature in presence of two witnesses.

BENJAMIN W. TUCKER.
